WELL PACKER

Clarence E. Burt, Los Angeles, Calif., assignor to
 Baker Oil Tools, Inc., Vernon, Calif., a corpora-
 tion of California

Application November 14, 1941, Serial No. 419,047

2 Claims. (Cl. 166—12)

This invention relates to well packers which are utilized in packing off, cementing, producing, and other analogous operations in oil and gas wells.

Well packers adapted to be run in casings are usually provided with packing members for effecting a seal between the packer body and the casing wall, and also with slips for securing the packer to the casing. These slips and packings are retained initially on the packer body in retracted positions to permit lowering of the packer device to the desired point in the well casing before the slips and packing are set. In some circumstances, conditions of the hole or casing cause premature setting of these casing engaging members, as for example, upon their encountering foreign substances within the casing which tend to force them to a setting position before the desired point in the casing or operating condition is reached.

It is therefore an object of the present invention to materially lessen, if not eliminate altogether, the hazards of premature setting of a well packer in a casing.

Where segmental slips are employed in a well packer, it sometimes happens that they do not all move uniformly from their retracted positions into anchoring engagement with the wall of the casing. Instead of remaining in alignment, the slips may occupy different longitudinal positions along the wall of the casing, tending to place the well packer in an off-center position therewithin and imposing excessive strains upon it.

It is a further object of the present invention to overcome this difficulty by maintaining the segmental slips or any set of packer anchoring members in alignment, and thus ensure their engagement with the casing while they are substantially in the same transverse plane.

Some forms of well packers, such as the packers known as "cement retailers," are removed from the casing by the rotary method of drilling after performing their particular functions in the well casing. Parts of the retainers have heretofore been difficult to remove by drilling, due to their tendency to turn with the drill bit, rather than remain stationary and enable the bit to pulverize them for easy conveyance in the drilling fluid to the surface of the hole.

Accordingly, it is another object of the invention to prevent rotating of well packer parts which are later to be removed from the casing by a rotary drilling or similar operation.

This invention has other objects that will be

come apparent from a consideration of the embodiment shown in the drawing accompanying and forming part of the present specification. This form will now be described in detail to illustrate the general principles of the invention, but it is to be understood that such detailed description is not to be taken in a limited sense, since the scope of the invention is best defined by the appended claims.

Referring to the drawing:

Figure 1 is a longitudinal view, partly in section and partly in elevation, of a well packer with its parts in retracted position;

Figure 2 is a view similar to Figure 1, with the well packer disclosed as set in packed off condition within a well casing; and

Figure 3 is a cross-section taken along the line 3—3 in Figure 1.

The well packer A may be lowered to the desired setting point in a well casing B on the end of a tubular string C, which is suitably coupled to the upper end thereof. The packer includes a main body 10 carrying a set of upper annular segmental tapered slips 11 adapted to be moved into engagement with the casing by an upper expander cone 12 initially retained in retracted position by one or more shear screws 13 attaching it to the main body. The upper slips 11 are similarly retained in retracted or ineffective position by shear screws 14 securing them to the cone 12. In addition, the upper ends of these slips 11 engage the lower surface of an abutment ring 15 threaded on the main body, with the slips held against the external cylindrical surface of the body by a split retainer ring 16 positioned within a circumferential groove 17 formed jointly in the exteriors of the slips, and bearing against the bottom of the groove 17 to hold the slips 11 snugly against the body 10.

A lower set of annular segmental tapered slips 18 is initially held in retracted position by attaching it to a lower expander cone 19 through the medium of shear screws 20, this latter cone being initially held in ineffective position by suitable frangible connections in the form of shear screws 21 threaded into the body. The lower ends of these slips also engage an abutment consisting of a flange 22 at the lower end 50 of the body and a valve housing 23 threaded on this flange. Upward movement of the slips 18 along the body 10 when in retracted position is prevented by pins 24 fixed to the body and extending outwardly into holes 25 provided in the slips. This pin and hole arrangement forms a

radially slideable connection between the body 10 and slips 18, which will prevent longitudinal movement of the slips along the body, but which still allows the slips to be shifted radially of the body by the tapered expander 12.

A packing sleeve 26 of synthetic or natural rubber is positioned on the body between and suitably secured to the ends of the expander cones 12, 19. This sleeve is initially retained in retracted position free from contact with the casing wall, but it is capable of being expanded into engagement therewith.

The valve housing 23 carries a tripping ball seat 27 therewith initially held in position by a shear screw 28. This seat has an upstanding arm 29 for holding a buoyant back pressure ball 30 in ineffective position against the interior of the housing to prevent its seating against a valve seat 31 at the lower end of the body 10. Removal of this arm 29 through a proper operation of the packer device permits the ball 30 to engage its cooperable valve seat 31 whenever reverse flow of fluids through the body tends to occur.

The packer A is run into the casing B to the desired point and circulation established therethrough to remove any undesired foreign matter. Thereafter, a tripping ball 32 is lowered or pumped down through the tubular string into seating engagement with the tripping ball seat 27, which permits the pressure of the fluid within the packer body to be increased for passage through ports 33 opening through the body into the interior of the packing. The fluid under pressure moves the upper cone 12 upwardly along the body to disrupt the shear screws 13, 14 and expand the upper slips 11 outwardly into gripping engagement with the casing.

It is to be noted that the abutment ring 15 prevents upward movement of the slips 11, thus causing their radial expansion upon longitudinal movement of the cone 12 along the packer body 10. After the upper slips have been set, the pressure of the fluid is increased to shear the pin 28 holding the tripping ball seat 27 in the valve housing 23, whereupon this seat together with its upstanding arm 29 is pumped from the well packer, so as to allow the closing of the back pressure valve 30, 31 whenever reverse flow of fluids tends to occur. The taking of an upwardly directed strain on the tubular string C and main body 10 then compresses the packing 26 between the casing wall and exterior surface of the body, while the continuation of this strain shears the screws 21 and 20 holding the cone to the body and the slips to the cone, causing the lower slips 18 to move along the cone 19 and radially into engagement with the casing B. The well packer is now in set position for the performance of a cementing, production or other operation, or to function as a bridge plug, as explained in United States Patent No. 2,121,051, to which attention is invited for further structural and operational details of this type of tool.

In the former designs of well packers, especially of the type above described, debris and other foreign matter in the well casing has sometimes caused premature tripping of the lower slips 18 while the tool was being run in the well bore. The mounting of the lower slips 18 so that they do not extend laterally beyond the confines of the valve housing 23, and their engagement while in retracted position with this housing and the body flange 22, prevents their being contacted detrimentally by foreign matter which

might tend to shear the screws 20 holding them to the cone 19 and force them upwardly therewith into engagement with the casing. Should debris or foreign matter tend to move the slips 18 upwardly, such action would be prevented by

the body pins 24 extending into the radial holes 25 through the slips. This pin and hole combination precludes upward movement of the lower slips along the body, without preventing their radial outward movement into engagement with the casing upon the taking of an upward strain on the body, as described above. In a similar manner, engagement of the upper slips 11 with the abutment ring 15 while they are in retracted position also guards them against premature tripping in the event of elevation of the well packer in the casing.

After the tripping ball 32 has engaged its seat 27 and the pressure of the fluid increased to elongate the packing 26, for the purpose of shearing the upper screws 13, 14 to move the upper slips 11 into engagement with the casing, the pressure within the tubular string C and tool may be bled off, allowing the packing 26 to return or contract to its initial position and move the cone 12 downwardly along the body 10. Ordinarily, the upper segmental slips 11 drop downwardly with the cone 12 and maintain their aligned position in engagement with the casing so as to keep the tool body centered therewithin. At times, however, one of the slips may drop ahead of the others, producing their disalignment and causing lateral strains of large magnitude to be imposed on the packer body 10 when the subsequent upward pull is taken on the tubular string C and body to pack off the tool and set the lower slips 18.

The split slip retainer ring 16 precludes the above-mentioned disalignment from occurring. Not only does this element engage the bottom of the composite circumferential groove 17 to hold the slips 11 against the body 10, but it also prevents the slips from disaligning in the event that the cone 12 is pulled back down along the body 45 by the packing member 26 upon relieving of the fluid pressure within the tool. It is readily observed from the drawings that the split ring 16 bridges the gaps 11a between the segments and couples them together for conjoint movement in a longitudinal direction.

This ring 16 preferably engages the bottom of the circumferential groove 17 and exerts a slight contracting force against the slips 11, holding them in engagement with the body. However, this force is insufficient to prevent radial expansion of the slips against the casing, nor is it great enough to pull the slips back inwardly upon retrograde movement of the cone 12. The retainer ring 16 is similar to an automotive piston ring, and may be made of cast iron or mild steel.

Difficulties have sometimes been encountered in drilling up well packers after they have performed their function in the well bore, due to the rotation of the body in the expander cones 65 under the influence of the drill bit. As the bit is rotated by the drilling string, the body merely revolves with it within the cones, which are held stationary by the slips, so that the necessary relative motion between the drilling bit and body does not occur to effect its removal.

The present invention overcomes this difficulty by keying the bottom cone 19 to the body 10 in such manner as to prevent relative rotation therebetween while permitting relative longitudinal movement to occur. The specific key dis-

closed in the drawing consists simply of a keyway 33a formed lengthwise along the exterior of the body which is cooperable with a ball key 34 seating partially within the keyway and partially within a hole 35 drilled through the cone 19. Outward movement of the ball from the keyway 33a and through the hole 35 is prevented by a set screw 36 threaded within the hole and engaging the ball 34.

It is readily apparent from this construction that the body 10 cannot rotate with respect to the cone 19, enabling the rotary drill bit to disintegrate it together with the other packer parts. However, the body 10 may be pulled upwardly within the cone 19 without restraint from the ball lock and keyway combination.

A well packer has thus been provided which overcomes certain disadvantages of former designs. Premature tripping of the slips is prevented, the slips are maintained in alignment, and the packer parts are so coordinated as to facilitate their drilling up whenever such action becomes essential or desirable.

I claim:

1. A well packer, which includes a body having a lower abutment secured rigidly to it, normally retracted tapered slips arranged around said body, a downwardly converging tapered expander slidable along said body within said slips for moving said slips into engagement with the wall of said well casing to anchor said well packer therein against downward movement, frangible means securing said slips to said expander in retracted position within the confines of said

lower abutment and with their lower ends engaging said lower abutment, means on said slips and body forming a radially slidable non-shearing connection while said slips are in retracted position to prevent upward longitudinal movement of said slips along said expander prior to disruption of said frangible means, said radially slid able connection allowing said slips to be shifted radially of said expander into engagement with said casing wall upon disruption of said frangible means.

2. A well packer, which includes a body having a lower abutment secured rigidly to it, normally retracted tapered slips having radial holes therein and arranged around said body, a downwardly converging tapered expander slid able along said body within said slips for moving said slips into engagement with the wall of a well casing to anchor said well packer therein against downward movement, frangible means securing said slips to said expander in retracted position within the confines of said lower abutment and with their lower ends engaging said lower abutment, non-shearing pins secured to said body and slidably fitting in said holes while said slips are in retracted position to prevent upward longitudinal movement of said slips along said expander prior to disruption of said frangible means, said pin and hole connection allowing said slips to be shifted radially of said expander into engagement with said casing wall upon disruption of said frangible means.
